UNITED STATES PATENT OFFICE.

WILLIAM JOSEPH ANDERSON, OF HYDE, ENGLAND.

DISPLAY STAND.

Application filed June 24, 1920. Serial No. 391,479.

To all whom it may concern:

Be it known that I, WILLIAM JOSEPH ANDERSON, a subject of the King of England, residing at 1 Meadow Avenue, Hyde, in the county of Chester, England, have invented certain new and useful Display Stands, of which the following is a specification.

This invention relates to display stands, menu, photograph, and show-card holders and like articles, which are constructed of cardboard or like material, and has for its object to provide, in combination, a permanent collapsible base stand or support structure which may be readily "knocked-down" or collapsed for transport or storage and when erected, shall be stable, strong and rigid; and a refill or "perishable" card or the like, which is detachably or removably held or gripped by said base stand or support when the latter is erected.

A base or stand, according to my invention, essentially embodies two parallel lath-like pieces or portions which are secured side by side together by means of a wire staple or staples, bifurcated fasteners, wire stitching, or in any other convenient manner; two panel-strut or support members respectively integral with the lath, and which are created by longitudinally creasing or hinging the cardboard or like material; and means whereby said panel struts or supports are maintained in spread or inclined position when the stand is erected and in use.

A characteristic feature of the stand is that said lath-like members form—or tend to form—in effect jaws which are caused to grip a refill or "perishable" piece of cardboard, or the like, placed between same when said panel strut members are forced apart.

In order to facilitate the insertion of a refill card, or the like, between said upper lath-like members, one of the latter may be so cut as to expose partially—or wholly—the upper portion of the other, and distance or buffer pieces may be inserted between the lath ends.

I will further describe my invention with the aid of the accompanying sheet of explanatory drawings, which illustrate, by way of examples only, two modes of embodying same.

In said drawings:—

Fig. 1 is an elevation, and

Fig. 2 a side view of a display stand and refill according to one arrangement.

There is provided a piece of cardboard generally designated —a— which is creased or hinged along the lines *b*, *c*, *d*, *e*, so that there are created lath-like strips or members *f*, *g*, side panel struts or supports *h*, *i* and a base *j*, the ends of said laths *f*, *g* are permanently secured together by means of wire staples *k*, *k*.

l denotes a refill card, such, for instance, as a menu card, which is adapted to be inserted between said laths *f*, *g*. Due to the construction of the base, the simple pressure of finger and thumb at the creased ends of the panel struts when the stand is collapsed causes the jaws to open or gape, so that the refill may be readily inserted.

When the stand is in use, said strut panels *h*, *i*, are spread apart in which spreading motion the refill card *l* is gripped between the laths *f*, *g*.

The middle or base *j* is longitudinally creased or hinged on the line *m* so as to permit of complete collapse of the stand; but to prevent accidental collapse thereof, a piece of cardboard or the like *n* is pivoted to the underside of said base *j* by means of a bifurcated fastener *o*, or the like.

On positioning said piece *n* transversely of the middle base crease *m* when the stand is erected the rigidity of same is ensured.

One of said lath members *g* is so cut at *p* as to expose the upper portion of the other lath *f* in order to provide a guide for facilitating the insertion between the laths of the lower end of the refill card *l*.

The refill card *l* illustrated is formed with a tongue *l'*, but, of course, said tongue may be omitted, if desired; and in order to create a permanent opening or gap for the refill between the laths *f*, *g* small distance or buffer pieces of cardboard, or the like, may be fitted between the laths at their ends.

It is to be understood that the longitudinal crease or hinge *m* designed to permit of collapsibility of the stand may be arranged at any convenient position in the base.

A stand constructed as before described is stable, and not readily knocked over when erected.

It is intended that said base stand or support shall be of a "permanent" nature, carrying any desired advertising matter, and where necessary as in the case of a menu support, the advertising matter will appear on both sides so as to be visible from both

sides of a table; in this application of the invention, both sides of the stand will be equal, that is free from mutilation, by way of cut-out or added parts.

5 What I claim is:—

A display stand made from a piece of cardboard bent to triangular form with its apex adapted to support an article and its base creased to afford a hinge to permit of 10 said stand being collapsed, and a piece of

cardboard pivotally mounted on the under side of the stand base and adapted to extend transversely of the base crease when the stand is erected.

In testimony whereof I affix my signature 15 in the presence of two witnesses.

WILLIAM JOSEPH ANDERSON.
